WILLIAM W. GREEN, JR., OF JANEVILLE, WISCONSIN, ASSIGNOR
TO HIMSELF AND E. BROWN, OF SAME PLACE.

Letters Patent No. 84,352, dated November 24, 1868.

IMPROVEMENT IN DEVICE FOR HOLDING DOORS OPEN.

The Schedule referred to in these Letters Patent and making part of the same.

To all whom it may concern:

Be it known that I, WILLIAM W. GREEN, Jr., of Janesville, in the county of Rock, and State of Wisconsin, have invented a new and improved Device for Holding Doors Open; and I do hereby declare that the following is a full, clear, and exact description thereof, which will enable those skilled in the art to make and use the same, reference being had to the accompanying drawing, forming part of this specification, in which the drawing represents a central transverse section of my invention, the object of which is to prevent the door or the knob of the lock from marking the wall by striking against it when the door is swung open, and also to catch automatically, and hold the door open.

It consists in the construction of a spring-catch, passing through a knob affixed to the washboard or surbase of a wall in any suitable position, and adapted to secure the knob to the wash-board, and to catch into a socket-plate affixed to the bottom of the door, as will be hereinafter more fully described.

In the drawings—

A is the knob, affixed to the surbase or washboard B by means of a screw-thread in the shank a of the knob.

The shank a bifurcates near its outer or free end, and thus forms two branches or spring-tines, b b, each having a head which tapers to front and rear, and the

two heads, when sprung together, form a diamond or spear-shaped termination, which catches in the socket-plate covering a socket or recess, D, in the door C.

The tines b b are located in a hole or recess, h, in the knob, and the heads d d are presented beyond the said recess to catch in the plate e e, as shown.

A rubber washer, f f, or other elastic device is affixed on the end of the knob, to prevent any concussion of the door.

A small block, having a cavity, D, and the plate e e, may be employed to affix to the door, if desired, instead of forming the cavity in the door itself.

I am aware of the existence of door-holders in which a metal or rubber spring is adapted to hold the door open, but this I do not claim.

I claim as new, and desire to secure by Letters Patent—

The holder, having the bifurcated end d d, adapted to fit within the plate e attached to the door, and with a shoulder at the inner end of the bifurcation, by which the knob A is held to the wash-board B, as constructed and shown.

WILLIAM W. GREEN, JR.
